UNITED STATES PATENT OFFICE.

CHARLES GREENOUGH MORTIMER, OF EAST ORANGE, NEW JERSEY, ASSIGNOR TO
NATIONAL BINDING MACHINE COMPANY, OF NEW YORK, N. Y., A CORPORA-
TION OF NEW YORK.

STRIP-SERVING DEVICE.

1,384,081.

Specification of Letters Patent. Patented July 12, 1921.

Application filed January 17, 1914, Serial No. 812,692. Renewed October 30, 1920. Serial No. 420,851.

To all whom it may concern:

Be it known that I, CHARLES GREENOUGH MORTIMER, a citizen of the United States of America, and a resident of East Orange, in 5 the county of Essex and State of New Jersey, have invented an Improvement in Strip-Serving Devices, of which the following description, in connection with the accompanying drawings, is a specification, like characters on the drawings representing like parts.

The present invention has to do with improvements in apparatus for preparing and serving strips of tape to be applied to packages, boxes and the like. The object is to 15 provide an apparatus whereby the tape may be in prime adhesive condition immediately upon delivery from the machine. It has been found in practice that, with the use of gummed tape which is subsequently passed 20 through a machine for moistening and serving, the adhesiveness of the remoistened gum or glue is very often imperfect, due either to an improper amount of water being supplied to the surface thereof or to the fact 25 that insufficient time is allowed for the glue and water to combine. Moreover it is difficult to produce and apply a glue which will universally remoisten to a proper degree of stickiness and at the same time, normally 30 remain hard enough to avoid adhesion in the roll under varying conditions of humidity and temperature.

To overcome the difficulties outlined above, I have invented an apparatus whereby irrespective of climate, gummed or ungummed 35 tape may be converted into adhesive strips having the exact degree of stickiness necessary for the particular use to which they are to be applied. This result may be obtained 40 in the case of previously gummed tape by moistening the same freely and then tempering the moistened surface to the proper degree of stickiness. In the case of ungummed tape, an adhesive may be applied in liquid 45 form and then tempered to the desired degree. The invention therefore, contemplates an apparatus in which a supply of tape is reduced to strips which are served successively from the machine in prime condition to adhere firmly to any given article or substance. I have illustrated an embodiment 50 of my invention in the accompanying drawings, in which,

Figure 1 is a side elevation with a part in 55 section and with parts broken away to show

the interior of the tempering member and means for heating the glue or other adhesive.

Fig. 2 is a detail illustrating the construction of the upper moistening roller. 60

Figs. 3, 4, and 5 are detailed views showing the mechanism for controlling the moistening and drying feed rollers.

Fig. 6 is a detail illustrating the arrangement and construction of the rollers in the 65 drying member, and,

Figs. 7, 8, and 9 show details of the mechanism for feeding and cutting strips of tape of predetermined length.

Referring to the drawings, A represents 70 any suitable automatic tape feeding and cutting mechanism wherein the strip serving and cutting means may be actuated from a common shaft rotating continuously in one direction. B represents a moistening device 75 or means for applying an adhesive and C constitutes a drying member wherein the moistened or gummed strip may be tempered or partially dried so as to be in prime condition for affixing to a package or the 80 like. In order that the feeding rolls of the three members A, B, and C may operate in proper coördination, suitable mechanism is provided to connect these three members and to synchronize the feed rolls thereof. 85 It may also be desirable under some conditions, to operate continuously the feeding mechanism of member C or of B and C while the feeding mechanism of A remains 90 at rest.

As shown in the drawings, a driving shaft 1 is suitably journaled in the member A and operatively connected with the tape feeding and tape cutting mechanism thereof in any suitable manner. In the present embodiment of the invention, a feeding roll 56 mounted upon a shaft 57 is actuated by means of a gear 58 upon the shaft 1, which meshes with an intermediate gear 59 to drive in pinion 60 also on the shaft 57. The feeding roll 100 has a coöperating presser roll 61 suitably journaled in the casing and connected with the shaft 1 through the gears which are so arranged that the two rolls may have uniform movement. The roll 61 is held yielding 105 against the companion feeding roll 56 by a spring or other suitable device 62. A pair of guide rolls 63 and 64 are positioned between the feeding rolls and the tape supply, of which the web 65 passes under, be- 110

tween and over the guide rolls to the feed rolls 56 and 61.

In advance of the feeding rolls, there is located a stationary blade 66 under which 5 the web of tape passes as it is fed forward by the said rolls. A coöperating blade 67 suitably pivoted at 68 is actuated by a cam 69 secured to a shaft 69^a suitably mounted in the framework of the member A. In 10 order that the shaft 69^a may rotate continuously and at the same rate as the main shaft 1, it is operatively connected therewith through suitable gearing, consisting of a gear 92 fixed on the shaft 1, a pinion 93 fixed 15 on the shaft 69^a, and an intermediate gear 94. The stroke of the coöperating blade is coincident with the pause of the feeding action hereinafter described and is made 20 against tension of the spring 70 which causes the blade to return to normal position immediately upon being disengaged from the cam 69. The severed strip then continues 25 to cross over a moistening roll 38 located adjacent to the cutting mechanism and arranged to rotate in a tank 37 as hereinafter described so as to synchronize the forward movement of tape through the feeding rolls and over the moistening roll.

At the side of the casing of the member 30 A opposite the main pulley, are extended casings 71 and 72 which serve to inclose working parts of the strip feeding and cutting mechanism. The casing 71 may be provided on its outer face with a dial 73 (Fig. 9) 35 and on its peripheral surface with stop openings 74, which dial and stop openings, in conjunction with an indicator arm 75 having a pointer 76 and a spring presser plug 77, not only indicate the length of the tape which 40 will be fed from the machine, but, in connection with a pawl mechanism, actually determine the same. A pawl arm 78 is fastened upon the main shaft 1 and adapted to engage a ratchet 79 mounted upon a sleeve 80, 45 also carrying the main gear 58 and loosely mounted on the shaft 1. This engagement is effected through the agency of a cam pawl 81 pivoted to the arm 78 and provided with a cam member 82, but it may be moved and 50 released from the ratchet 79 whenever the cam 82 passes an adjustable trip consisting of a member 83 which projects through a slotted opening 84 in the casing and is adapted to be fastened in any desired position of adjustment along the said opening by means of a nut 85. In operation the pawl 81 is thrown out of engagement with the ratchet 79 by means of this trip thereby 55 stopping the feeding action of the said rolls 60 and of the parts for handling the strip of tape. A spring 86 normally tends to hold the pawl 81 in engagement with the ratchet 79 and, in order to secure positive contact between the two latter, the end of the pawl 65 is preferably made with two points to con-

form to the shape of the teeth of the ratchet. Arranged upon the upper surface of the pawl 81 is a detent 87 which, when the cam portion is depressed by the trip 83, is engaged by a trigger 88 pivoted to the 70 arm 78 at 89 and having an offset pawl 90 arranged in a plane so as to be engaged by the spring plug 77 which, as previously pointed out, may be adjusted to project through any of the several openings 74 corresponding to the markings on the dial 73. Thus when the central shaft is rotated, the pawl 81 remains in engagement with the ratchet 79 thereby transmitting a feeding movement to the roll 56 until the cam 82 is 80 depressed by the trip 83. Thereupon the end of the trigger member 88, actuated by a spring 91, drops into the detent 87 and holds the pawl 81 out of engagement with the ratchet until the offset pawl member 90 engages the spring pressed plug 77 thus releasing the pawl 81 so that it may reengage 85 the ratchet 79. From the foregoing, it will be seen that a complete cycle of operation is effected upon each complete rotation of 90 the main shaft to which power is imparted through a pulley 2.

I have also provided mechanism whereby the feeding function of the moistening device B may be suspended during the operation of severing the tape. A beveled gear 3 and a disk 4 having slots 5 are fixed to the shaft 1. A coöperating disk 6 loosely mounted upon the said shaft adjacent to the first mentioned disk, is provided with a 100 headed pin 7 passing through a perforation near its periphery and in such a position as to readily engage a slot in the disk 4 when one of them comes into alignment with the pin 7. A gear 8 is mounted on the same 105 sleeve with the disk 6 and is adapted to mesh with a second gear 9 mounted on a shaft 10 which is journaled in a suitable part of the framework of the member A. This shaft 10 also carries a cam disk 11 and a notched disk 12. It is contemplated that the main shaft shall rotate continuously and that the gears and disks 6 hereinabove described shall be set in operation whenever the pin and slot connection is made with the main shaft. To control this mechanism a lever arm 13 is pivoted at a point adjacent to the periphery of the disk 6. A wedge shaped projection 14 is mounted upon the 110 said lever arm in the path of the head of the pin 7 which is held normally in spring pressed engagement with the side of the disk 6. In operation, the flange of the headed pin engages the narrow end of the wedge 14, as the disk 6 rotates, and the pin is thereby forced out of engagement with one of the slots 5. This serves to disconnect the disk 6 and its corresponding gear 8 from operation by the main shaft. The wedge 14 becomes operative only when the notch 15 in 115

the disk 12 engages a corresponding projection 16 on the lever 13.

A shaft 24 journaled at 17 and 17^a carries at one end a beveled gear 18 which meshes 5 with the beveled gear 3 mounted on the main shaft 1. At the other end is a pulley 19 fixed to a sleeve 26 which is loosely mounted on said shaft and connected by means of a belt 20 to another pulley 21 fixed to a shaft 10 22 which carries the roll 23 of the moistening mechanism of member B. This shaft and pulley connection is designed to normally connect the roller 23, and by means of suitable gearing, the feeding rolls of the 15 member C, with the main shaft 1. Under normal conditions it is desirable that all of the feeding rolls remain inert during the severing operation. To this end the shaft 24 is provided carrying a slideable sleeve 25 20 which rotates with the said shaft but is adapted to be slid back and forth thereon. The adjacent faces of the above mentioned sleeves 25 and 26 are serrated to form a clutch connection between the two. The 25 sleeve 25 is further provided with a peripheral groove 27 in which a yoke 28 is adapted to engage the latter forming the upper extremity of a rocker arm 29. The latter is suitably journaled in the frame work of the 30 member B so that its lower extremity may normally rest in the path of the cam 30 mounted on the periphery of the cam disk 11. A spring 31 bearing against an end of the sleeve 25 holds the same normally in engagement with the coöperating sleeve 26 to 35 operate the feed rolls of the members B and C. This condition obtains when the lever 13 is in the position shown in Fig. 3; but when the lever is pressed downwardly, the 40 projection 16 is disengaged from the notch 15 and the cam disk 11 is permitted to rotate so that the cam 30 will periodically engage the extremity 32 of the lever arm 29 thereby momentarily disconnecting the feeding 45 rolls of members B and C from action of the driving shaft 1. This is the normal condition of operation and may be made continuous by providing a suitable device for holding the lever arm 13 in its lower- 50 most position so that the projection 16 will not engage the notch 15. This may be done by means of a treadle as 33 which is connected to the lever arm by means of a rod 34 the said treadle being adapted to be pushed 55 downwardly against pressure of a spring 35 and to be held in this lower position by means of a suitable latch 36.

The member B comprises a tank 37 adapted to contain either an adhesive substance or 60 water, a roller 38 mounted to rotate in the said medium and to carry up with it upon its surface a layer sufficient to provide the strip of tape with a coating of glue or, in case the tape is already gummed, to moisten 65 the gum thereon. This roll is positively ac-

tuated by connection with the main driving shaft heretofore described. A coöperating roll 39 mounted above the last mentioned roll is provided with peripheral projections 40 which press against the tape as it passes 70 between the two and present a minimum of surface for the collection of glue which, in sufficient quantities, would interfere with operation of the machine. A guard or stripper 41 may be positioned adjacent to 75 the rolls to prevent the tape from curling upwardly and further to guide the strip toward the opening 42 in the member C. A plurality of narrow guide members 43 may also be mounted adjacent to the feeding roll 80 to prevent the tape from curling downwardly. Where ungummed paper is used in the present apparatus, it is necessary to apply a coat of adhesive which may be supplied from the tank 37. This should preferably be kept at a warm temperature, for which purpose I provide a coil of steam pipes 44 underneath the tank 37, although it is obvious that other means may be used with similar effect. 90

When the tape has acquired a coat of glue on one of its surfaces, it is fed into the member C in order that the moist glue may be tempered to the proper degree of stickiness by reducing somewhat the percentage of 95 moisture which it contains. The member C comprises a hollow chamber provided with feed rolls which carry the strip through the chamber and heating means such as a coil of steam pipes for drying the glue. The 100 feeding rolls 45 are actuated by means of a gear connection 46 between the latter and the driving gear of the member B. An opening 47 is provided in the upper portion of the chamber 48 for the purpose of regulating the temperature therein and the current of heated air passing through the chamber may be regulated by means of a damper, as 49, or by a blower adapted to inject a column of air into the chamber 105 110 through suitable openings. The feed rolls 45 are also provided with peripheral projections 50 which impinge against the gummed surface of the tape as it passes through the tempering chamber without 115 however adhering thereto. Coöperating with these rolls 45 are ordinary flat rolls 51 adapted to be held in yielding engagement with the feed rolls to provide positive gripping means for feeding the tape. In order 120 that the projections 50 of the feed rolls 45 may not become clogged with glue, suitable scraping members 52 are positioned so as to engage the edges thus removing whatever glue may have adhered thereto. 125 Adjacent to each feeding roll is a plurality of gratinglike members 53 just below the normal path of the tape to prevent the same from bending downwardly in its course through the tempering chamber. 130

It will of course be advantageous to provide the tempering chamber with a suitable nonconductive covering for the purpose of conserving the heat therein. Where steam 5 is used a safety vent 54 may be provided and a stop cock 55 may be used to draw off condensed steam when the pipes have been permitted to cool. It is conceivable that many devices may be substituted to accomplish the 10 mechanical effects produced in the present apparatus without, however, departing from the essence of the invention hereinabove disclosed and which I conceive to be an apparatus having a tempering member so related 15 to means for severing and gumming strip of tape as to produce any desired condition of stickiness or adhesiveness on the said strip suitable for immediate application to the sealing of a package or the like.

20 I claim as my invention:

1. In a strip serving apparatus, the combination with means for supporting a roll of tape, of means adapted to feed the tape and to sever the tape automatically into 25 strips of predetermined length, means for conveying the successive severed strips automatically from said severing device, means to render adhesive one side of the severed strips, and means for absorbing 30 moisture from the adhesive material on said severed strips whereby said strips may be in prime condition for immediate application to a box, package or the like.

2. In a strip serving apparatus, the combination of means for supporting a supply 35 of tape, means for cutting the same into strips of predetermined length, means for making the severed strips adhesive on one side and means for partially drying the adhesive severed strips, consisting of a receptacle adapted to be heated and having means for drawing in and discharging the severed strips in prime condition for immediate application to a box, package or the like.

45 3. In a strip serving apparatus, the combination of means for supporting a supply of tape, means for severing strips of predetermined length therefrom, means for applying an adhesive solution of gum or glue 50 on the said strips, and means for tempering the gum or glue thereon to a prime adhesive condition, for immediate application to a box, package or the like, the gumming means being located between the severing means 55 and the gum tempering means.

4. In a strip serving apparatus, the combination of means for supporting a supply of ungummed tape, means for detaching strips of predetermined length therefrom, 60 means for applying an adhesive substance to one side of the detached strips, a hollow chamber having an opening adjacent to the last named means, a plurality of rolls adapted to engage the detached gummed strip and convey it through and out of the

said chamber, and means for heating the chamber.

5. In a strip serving apparatus, the combination of means for supporting a supply of ungummed tape, means for detaching strips therefrom, means for applying an adhesive substance to one side of the detached strips, a chamber fitted with coöperating rolls adapted to engage the detached gummed strips and convey them through 75 the said chamber, the said rolls being arranged vertically in pairs, the roll in each pair adjacent to the gummed surface being corrugated, means adapted to scrape the corrugated rolls, means for heating the 80 chamber, and means for regulating the heat in the chamber.

6. In a strip serving apparatus, the combination of means for supporting a supply of tape, strip feeding means, means for severing said strips from the supply, means for gumming the severed strips, means for tempering the gum on said severed strips, and means operatively connected with the strip severing means to actuate the feeding means 85 intermittently.

7. In a strip serving apparatus, the combination of means for supporting a supply of tape, means for automatically detaching strips therefrom, means for gumming the 95 said detached strips, and means for subjecting the gummed surface of the said detached strips to a current of heated air, whereby the strips may be in proper adhesive condition for immediate application to a box, 100 package or the like.

8. In a strip serving apparatus, the combination of means for supporting a supply of tape, means for feeding said tape from the supply, strip severing means, means for rendering the severed strips adhesive, means for tempering the gum on said severed adhesive strips, and means whereby the tape feeding means may be thrown into and out of operation independently of the severing, moistening, and tempering means.

9. In a strip serving apparatus, the combination of means for supporting a supply of tape, strip feeding means, strip severing means, adhesive applying and adhesive tempering means operative intermittently with said strip severing means, means independent of said adhesive applying and adhesive tempering means for arresting operation of said feeding means, and means whereby the adhesive applying and adhesive tempering means may be operated continuously during the inoperative period of said strip feeding means to clear the apparatus of adhesive strips.

10. In a strip serving apparatus, the combination with means for supporting a roll of tape, of means adapted to feed tape and to sever the tape into strips of predetermined length, means to render adhesive one 130

- side of the severed strip, an adhesive tempering chamber, means for advancing detached adhesive strips through said chamber, means therein for supporting said adhesive strips intermediate their ends while so advancing, means for presenting to the adhesive portion of said strips a current of adhesive tempering air, and means for varying the effectiveness of said current.
11. In a strip serving apparatus, the combination with means for supporting a roll of tape, of means adapted to feed the tape and to sever the tape into strips of predetermined length, means to render adhesive one side of the severed strips, an adhesive tempering chamber, means for applying heat to said chamber, means for advancing the detached adhesive strips through said chamber, and means therein for supporting said strips intermediate their ends while so advancing.
12. In a strip serving apparatus, the combination with means for supporting a roll of tape, of means adapted to feed the tape into successive strips, means to render adhesive one side of the strips, an adhesive tempering chamber, means for advancing
- adhesive strips through said chamber, means therein for supporting said adhesive strips intermediate their ends while so advancing, and means for presenting to the adhesive portion of said strips a current of adhesive tempering air.
13. In a strip serving apparatus, the combination with means for supporting a roll of tape, of means adapted to feed tape in successive strips, means to render adhesive one side of the strips, an adhesive tempering chamber, means for advancing the adhesive strips through said chamber, means therein for supporting said adhesive strips intermediate their ends while so advancing, means for presenting to the adhesive portion of said strips a current of adhesive tempering air, and means for varying the effectiveness of said current.

In testimony whereof, I have signed my name to this specification, in the presence of two subscribing witnesses.

CHARLES GREENOUGH MORTIMER.
